US00D990350S

(12) **United States Design Patent** (10) Patent No.: **US D990,350 S**
(45) Date of Patent: **** Jun. 27, 2023**

(54) **WATCH STRAP**

(71) Applicant: **SHENZHEN STARSHIP TECHNOLOGY CO., LTD.**, Shenzhen (CN)

(72) Inventor: **Yu Kuang**, Shenzhen (CN)

(73) Assignee: **SHENZHEN STARSHIP TECHNOLOGY CO., LTD.**, Shenzhen (CN)

(**) Term: **15 Years**

(21) Appl. No.: **29/856,820**

(22) Filed: **Oct. 17, 2022**

(30) **Foreign Application Priority Data**

Sep. 13, 2022 (CN) 202230603625.2

(51) **LOC (14) Cl.** **11-01**

(52) **U.S. Cl.**

USPC **D11/3**

(58) **Field of Classification Search**

USPC D11/1-6; D10/32

CPC A44C 5/00

(57) **CLAIM**

The ornamental design for a watch strap, as shown and described.

DESCRIPTION

FIG. 1 is a perspective view of a watch strap showing my design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is an enlarged top plan view thereof; and,

FIG. 8 is an enlarged bottom plan view thereof.

The broken lines in the drawings depict portions of the watch strap that form no part of the claimed design.

1 Claim, 8 Drawing Sheets
